DRY PET FOOD AGITATOR/DISPENSER

Arthur L. Fassauer, P.O. Box 615, Canyon, Tex. 79015

Filed July 27, 1972, Ser. No. 275,862

Term of patent 14 years

Int. Cl. D30—03

U.S. Cl. D52—2 B

FIG. 1

FIG. 2

FIG. 3

FIG. 4

FIG. 1 is a perspective view of a dry pet food agitator/dispenser showing my new design;

FIG. 2 is a right side elevational view thereof, the left side being a mirror image thereto;

FIG. 3 is a top plan view thereof; and

FIG. 4 is a bottom plan view thereof.

I claim:

The ornamental design for a dry pet food agitator/dispenser, as shown and described.
